UNITED STATES PATENT OFFICE.

CHARLES W. BAILEY AND JOHN HAMMOND STEWART, OF LYNN, MASSACHUSETTS; SAID BAILEY ASSIGNOR TO SAID STEWART.

BLANK-FEEDING MECHANISM.

1,325,185.

Specification of Letters Patent. Patented Dec. 16, 1919.

Continuation in part of application Serial No. 17,009, filed March 25, 1915. This application filed November 20, 1915. Serial No. 62,632.

To all whom it may concern:

Be it known that we, CHARLES W. BAILEY and JOHN HAMMOND STEWART, both citizens of the United States, and residents of Lynn, 5 in the county of Essex and State of Massachusetts, have invented certain new and useful Improvements in Blank-Feeding Mechanism, of which the following is a specification.

10 The present invention relates to a feeding and packing mechanism adapted to take specific articles, such for example as blanks which are to be operated upon, carry such blanks to the operating position and pause 15 while the designed operation is being performed, and then proceed with the blank to a depository. The specific mechanism here illustrated was designed and applied as the blank feeding mechanism in a cutting machine for which we have jointly applied for 20 patent March 25, 1915, Serial Number 17,009, such machine being designed to clip or trim the ends of blanks for shoe counters, and the feeding mechanism being designed 25 to propel counter blanks into the operating position and remove them from such position after being operated upon.

The present application, therefore, so far as it embodies the blank feeding, guiding, 30 and holding means shown in the application above identified, is a continuation of said application as to all common subject matter.

We have further designed and applied to 35 the machine disclosed in the said application, a depository in which the blanks or other articles are packed by the conveying mechanism, and such depository also forms a part of the present application for which we desire protection.

40 Although the specific embodiment of our invention here shown is particularly designed and adapted for the purpose above indicated, we declare that the generic invention involved in the apparatus is not limited to that specific purpose.

In the drawings wherein we have illustrated the invention,

50 Figure 1 is a plan view of so much of the cutting machine illustrated in our former application Serial Number 17,009, filed March 25, 1915, as is necessary to show the construction and arrangement of our blank feeding mechanism.

Fig. 2 is a side elevation of the machine with parts in section on line 2—2 of Fig. 1. 55

Fig. 3 is an elevation on a somewhat larger scale of the depository in which the articles transported by the conveying mechanism are packed, showing also the adjacent end of the conveyer.

Fig. 4 is a sectional view of the parts shown in Fig. 2, the section being taken on the plane of line 2—2 of Fig. 1.

Fig. 5 is an end view partly in section of the depository as seen from the right of Fig. 3.

Fig. 6 is a detail elevation and section taken on line 6—6 of Fig. 3.

Fig. 7 is a sectional view of a detail taken on the line 7—7 of Fig. 3.

Fig. 8 is an elevation on an enlarged scale of the device, also shown in Fig. 2, which bears upon and retards the work pieces.

Fig. 9 is a detail section on line 9—9 of Fig. 8.

Fig. 10 is a front elevation of so much of the machine as exhibits the driving mechanism of the conveyer.

Fig. 11 is a sectional view on line 11—11 of Fig. 10.

The same reference characters indicate the same parts in all the figures.

Referring to the drawings, 10 represents generally the frame of the machine on which is mounted a work table 11 having a forward extension 12 whereon the blanks or work pieces are laid in position to be engaged by the feeding or propelling mechanism. 13 represents the block which supports the blank while being operated on, and 14 is a gripper adapted to hold the piece on the block 13. These parts and the means for operating the gripper are fully described in our prior application above identified and require no repetition of such description in this application. 95

The blank feeding element or blank feeder proper consists of two chains 15 and 16 which pass over driving sprockets 17 at the front of the machine, travel toward the rear of the machine in grooves or guideways in the table 11, pass over guide pulleys 18 and thence down and under guide pulleys 19, forwardly and around guide rolls 20 at the forward part of the machine, and up to the sprockets 17. The chains thus constitute 100 105

endless conveyers which travel in parallel and at the same speed (because the two sprockets with which the chains are severally engaged are of the same size). The 5 sprockets 17 and guide wheels 18 are located so that the upper boundaries of the conveyer chains will lie substantially flush with that part of the work holding block 13 against which the gripper 14 presses the 10 work, and the guideways or channels for the chains in the table and in such block have sufficient depth to secure this result, as appears clearly from Fig. 9.

The conveyer chains are caused to propel 15 the work pieces positively by means of fingers 21, which are connected to or formed upon certain links of the chains at definite intervals, and project upwardly as shown in the drawings above the plane of the table 20 11 and above the block 13. The work pieces adapted to be fed by this feeding mechanism are shown at 22. This particular piece is a shoe counter blank, that is a strip of leather or other suitable material adapted to 25 be formed into what is known in the art as a shoe counter, which is a stiffener for the rear part of a shoe upper. In the further description herein the work pieces operated on will be referred to as "counter blanks" 30 or simply as "blanks," for convenience of description and without intent to limit the invention to any specific use or connection with any specific machine.

The fingers 21 on the two chains are 35 opposite to one another, as appears in Fig. 1, whereby they are adapted to engage a blank at two separated points and hold the same perpendicular to the line of feed. Blanks laid upon the table extension 12 between 40 the gages 23, 24, and just in rear of the vertical plane through the axis of sprockets 17 will be caught by the conveyer fingers and fed.

A presser or retarding device is provided 45 to bear upon the blanks between the conveyers and exert a drag thereon sufficient to maintain the blanks in firm engagement with the fingers which propel them and prevent the blanks from getting out of position. 50 The presser is shown in its operative position in Figs. 1 and 2 and in more detail in Fig. 8. The presser is supported by a shaft or rod 25 held by lugs or brackets 26, 27 somewhat in rear of the position where the 55 blanks are engaged with the conveyer, and arranged to bridge the conveyer. The presser itself is constituted by a bar 28 and a forked arm 29 which are positioned by a frame 30, 31 rigidly secured on the bar 25. 60 A portion 32 of this frame surrounds the bar 25 and is secured by a set screw 33 so that the frame is restricted from moving. The part 30 of the frame projects directly 65 toward the table while another part 31 of the frame extends on a gradual incline rear-

wardly toward the table. The bar 28 extends from one part to the other and is contained at its ends in recesses therein and held by pins 34, 35 set in these arms and passing through slots 36, 37, respectively, 70 of the bar. A spring 38 interposed between the bar and the arm 31 presses the bar toward the table in a yielding manner, permitting it to rise when a blank is carried under it. Preferably the slots 36 and 37 75 are limited to this extent, that the bar hangs by the upper ends of the slots on the pins 34 and 35 slightly above the table to insure easy passage of the blank under the forward end of the bar. 80

The forked arm 29 has a web portion 39 at its forward end which is contained in the recess or fork on the end of arm 31 and is provided with a slot or elongated opening 40, which receives a pin 41 whereby the 85 member 29 is anchored but permitted to rise and descend. A spring finger 42 fixed at one end to the frame arm 31 bears on the rib 39 and presses the member or forked arm 29 toward and against the table. The 90 rear part of the member 29 is the part which is forked, as shown in Fig. 1; and this part consists of two branches 43, 44 which extend rearwardly between the two conveyer chains and on opposite sides of the gripper 14 and 95 that part of the block 13 against which the blank is pressed by the gripper.

Fig. 8 shows the relation of the chains and the blank fed thereby to the presser or retarder just described. The blank, on encountering the bar 28, raises and passes under the latter and is subjected to the pressure applied by the spring 38. The blank then passes under the member or forked arm 29 and is subjected to the pressure of the spring finger 42 continuously until it reaches the position for being operated upon. The friction of the presser exerts an appreciable drag upon the blank at 100 a point between the two conveyer chains, thereby causing the fingers of both chains to press squarely against the blank, preventing the blank from becoming skewed or inclined, and also preventing it from being dislodged to one side or the other by any vibration to 105 which the machine might be subject.

An intermittent motion is given to the conveyer chains in order that they may pause while the blank is in the working position and is being operated upon. The 110 shaft 45 on which the sprockets 17 are mounted carries a spur gear 46 meshing with a gear 47 on a shaft 48, which latter is driven by a shaft 49 through miter gears 50, 51. Gear 47 is loose on shaft 48 and is 115 frictionally driven by means of a disk 52 which may be of wood, or may be provided with a wood or leather face next to the gear, and which is splined to the shaft and is pressed toward the gear 47 by a spring 53 120

reacting against an abutment 54. The disk 52 represents a type of friction clutch.

Fixed upon the sprocket shaft 45 is a disk 55 having a notch limited by a shoulder 56.

5 Two notches are shown here. A stop or latch 57 is pivoted on an axis parallel to the shaft 45 and extends under the disk 55. Connected to it is an arm 58 which is pulled upon by a spring 59 so as to press the stop 57 against the rim of the disk 55. Stop 57 has a finger 60 projecting toward the shaft 48, and on the latter is a cam 61 in the same plane with the finger 60 and so projecting that it is adapted to strike the finger on 10 each rotation. The direction of rotation turns the disk so that its shoulder 56 is carried toward the stop 57, which being actuated by the spring 59 is caused to obstruct said shoulder and stop the shaft 45. Of course the disk is proportioned as to its size and speed of rotation, and the shoulder 56 and stop 57 so positioned, with respect to the number and locations of the feed fingers, as to arrest the conveyer chains when each 15 blank reaches the operating position. When the conveyer and the driving gear 47 are thus arrested, the clutch 52 slips while the shaft 48 continues in rotation. The cam 61 thus continues to rotate and when it strikes the finger 60, it displaces the stop 57, allowing the conveyer drive to be resumed. The position of the cam projection and its speed of rotation are so related to the location of the stop disk shoulder and its speed of rotation as to give time for performance of the 20 designed operation on the blank while the feeding mechanism pauses.

After being operated on, the blank is further propelled to a depository which is 25 located in rear of the guide wheels 18 and consists of stationary curved walls 65 and 66, and a movable wall or retainer 67. The wall 65 is composed of two plates which are arranged side by side and are somewhat 30 separated, as shown in Figs. 1, 5, and 6. These plates are supported by brackets formed by means 68 secured to the machine frame and extending rearwardly therefrom, and braces 69. The wall members 65 are 35 located immediately in rear of the wheels 18, from which they extend vertically downward, or approximately so, and are curved on a curve of wide radius tangent to the supporting beams 68, whereon they extend 40 rearwardly in a substantially horizontal direction, or preferably on a slight downward inclination. The upwardly extending parts of the wall 66 are braced by straps 70 secured thereto and bolted to the bracket 71, 45 which holds the guide wheels 18. A guide 50 72 passes from the upper part of the wall 65 over the wheels 18 and its upper edge is carried somewhat in front of such wheels and below the conveyer chains, as shown in 55 Fig. 4, being slotted to receive such chains.

The purpose of this guide is, of course, to carry the blanks over the wheels and into the depository without permitting the blanks to fall off the chains or become so skewed as not to enter the depository.

70 The wall 66 forms the rearward limit of the depository. It consists of two laterally separated members which are connected to a crossbar 66^a, which latter is supported by the wall 65 and held at the proper distance 75 therefrom by rods 73, each of which is secured to one of the members of the wall 65, being clamped thereto by its head and a lock nut 74, and extends rearwardly therefrom through the crossbar 66^a. A spring 75 on 80 the rod in rear of the crossbar reacts against an adjustable abutment nut 76 and presses the crossbar forwardly and against a sleeve 77, which abuts against an adjustable nut 78 and forms the locating abutment for the 85 wall 66. The springs 75 enable the wall to yield and, if desired, to exert some pressure 90 yieldingly against the blanks placed in the depository.

95 79 represents a tongue or finger which projects from a point near the rear limit of the table 11 toward the depository between the conveyer chains and is designed to bear on the blanks with a yielding pressure and retain them in proper position, in a similar 100 manner to that of the retarding device previously described, until they pass over the guide 72. The tongue or finger 79 here shown is formed of the sharply bent central part of a resilient rod or wire, the ends of 105 which are secured in brackets 80 which are widely separated and give sufficient opportunity for resilient yielding of the tongue. Of course an equivalent element for the same purpose could have many another construction and arrangement.

110 The sides of the depository or cavity are defined and limited by side plates or walls 81 and 82 mounted adjustably on the members of the front wall 65 by slotted straps 83 and bolts 84, each of which passes through one of the straps and the adjacent wall. Thus the walls or guide plates 81 may be adjusted to increase or diminish the width of the receiving space.

115 The part 67 which forms the bottom of the receiving space or depository before such space is filled, and after filling, serves as a back wall and support for the stacked articles, is slidingly mounted upon the wall 120 65 so that it may move from the position shown in dotted lines in Fig. 3 to that shown in Fig. 4, and progressively out to the extreme end of the shelf formed by the horizontal part of the wall 65, as indicated by 125 the full line position in Fig. 3 and in Fig. 2. For convenience of description I will call this part a back rest. It is formed as a plate or block having sufficient strength and of a form and area so corresponding to the 130

area of the blanks and their outline as to support the same securely. For the particular machine to which our invention is here shown as applied the back rest has the 5 outline shown in Fig. 6 and is adapted to support flat shoe counter blanks, but for other purposes it may of course have any other outline, and even for this purpose the outline is not material provided it is such 10 as to give support to the blanks.

The central part of the back rest is provided with a short and wide tongue 86, which projects into the slot between the two parts of the wall 65 and thereby guides the 15 back rest. On the ends of the back rest are rolls 87 which run against the exposed surface of the wall 65. A plate 88, which is provided with bearing pads 89 of some friction producing material, lies against the opposite side of the wall sections 65 and is 20 pressed against the same by a spring 90 on a stud 92, which passes from the back rest through the plate 88 and carries an adjustable nut 93 as an abutment 25 for the spring. In addition there are two spring braces 94 attached to the rear side of the back rest which slant toward and bear against the wall members 65. The back rest may be slipped freely along the wall and 30 around the bend thereof, and the friction caused by the bearing arms and the spring 90 is sufficient to hold it in any position, even in the position shown in Fig. 4, and when it supports a pile of blanks. The spring braces 35 94 are provided to support the outer part of the back rest and prevent the rest from becoming so inclined as to grip or clutch the wall 65.

It will be readily apparent that the blanks 40 fed by the conveyers are carried over the guide 72 and conducted by the latter into the depository space, in which the first to enter falls upon the back rest 67, and the succeeding blanks are assembled in a pile. The 45 top of the pile is always kept below the discharge point of the conveyer through the action of a packer or striker 95, which is secured to a rock shaft 96 oscillating in a bracket 97 at one side of the depository space. The packer projects over this space and is 50 caused to rise and descend thereover by oscillation of the shaft 96. Said shaft carries a gear segment 98 which meshes with a complementary gear segment 99 on a shaft 100, which latter is a part of the cutting machine 55 mechanism and is driven oscillatively by the main shaft 101 of said machine by the means fully set forth in our parent application Serial Number 17,009 March 25, 1915. Said shaft 100 carries an arm (shown in said parent application) which is oscillated by a crank and connecting rod mechanism geared to and driven by the shaft 49. The same shaft 101 also drives the shaft 49 by which 60 the feeding conveyer chains are actuated, as

explained in said parent application. The lower limit of swing of the packer or striker is below the plane of the blank feeding travel, and the packer is swung down and then up after each blank is deposited in the 70 receiving space. Thus when the top blank of the pile comes above the lower limit of the packer, the latter pushes the entire pile down, the back rest slipping under the positive pressure thereby applied. As the blanks 75 accumulate, and the accumulation is gradually advanced, the back rest and the accumulation of blanks swing around the bend in the wall 65, and travel toward the outer edge of the shelf. The back wall or retaining 80 wall 66 holds the blanks in the vertical part and the bend of the receiving space, preventing them from falling or being crowded out of the pile.

What we claim and desire to secure by 85 Letters Patent is:

1. A blank feeding and storing apparatus comprising a traveling conveyer, a guide wall extending downwardly from the discharge point of the conveyer and being curved into a substantially horizontal location, retaining walls arranged to define a blank-receiving space in rear of the upright part of said wall, a back rest movably supported on said wall, and a packer arranged to travel up and down over said receiving space for advancing said back rest and the blanks bearing thereon.

2. A blank feeding mechanism comprising in combination with a supporting table, 100 a flexible endless conveyer having a portion moving in substantially the plane of said table, a rod rigidly mounted so as to extend across said conveyer, a frame having divergent arms secured to said rod, a presser 105 hung from the arms of said frame in proximity to the table and to the conveyer, and a spring interposed between said presser and frame, forcing said presser toward the table so as to engage and retard a blank 110 propelled by said conveyer.

3. The combination with a table adapted to support blanks, of an endless flexible conveyer having a portion arranged to travel substantially in the plane of said table, a frame rigidly supported over said conveyer and pressing means connected to said frame adapted to bear on blanks engaged with said conveyer so as to retard the same, said pressing means including a member extending substantially parallel to said conveyer and being at its ends loosely coupled to said frame and extending therefrom over the table in such proximity thereto as to bear on a blank supported on the table, and a 125 spring secured to the frame and bearing on said pressing member between the ends thereof in a manner such as to force the same toward the table.

4. The combination with a pair of par- 130

allel endless conveyers, said conveyers having pushing means to engage and propel a blank, and a presser arranged between said conveyers and being forked so as to provide arms with an intermediate space, and means urging said presser toward the plane in which blanks are propelled by the conveyers.

5. A blank feeding flexible conveyer, 10 guiding means for causing said conveyer to travel in a substantially horizontal path and downwardly at the end of such path, guiding walls defining a downwardly extending receiving space at the rear end of such path, 15 a packer vibrated up and down over said space in synchronism with the travel of said conveyer, a movable back rest for the blanks in said receiving space guided to move in such direction as to enlarge such 20 space, and friction-causing means resisting movement of said rest.

6. In a blank feeding device the combination with a feeding conveyer, of a downwardly extending receiving space into which 25 the blanks are fed by the conveyer, means for moving said conveyer step by step, a packer or striker mounted to vibrate up and down in synchronism with the steps of the conveyer over said receiving space, whereby it

is adapted to apply pressure to each blank 30 placed on top of the pile in the receiving space, said receiving space being formed in part of a guiding wall which is curved from an upright to a substantially horizontal direction, and a back rest slidingly mounted 35 on said wall for supporting the blanks.

7. In a blank feeding and storing apparatus, a wall having substantially horizontal and upright portions connected by a gradual bend, said wall having an intermediate slot or guideway, a back rest supported on said wall and formed with a guide element lying in said slot or guideway and having a friction shoe bearing against the opposite side of the wall, whereby said back 45 rest is adapted to slide along said wall while being frictionally held at any position, retaining walls arranged adjacent to the upright part of said first named wall in positions to define a blank-receiving space, a 50 packer arranged to vibrate downwardly over said space and to press on the blanks therein, and means for delivering blanks to such space.

In testimony whereof we have affixed our 55 signatures.

CHARLES W. BAILEY.

JOHN HAMMOND STEWART.
